UNITED STATES PATENT OFFICE.

HENRY G. CLARK, OF DAYTON, AND LOUIS S. CLARK, OF COLUMBUS, OHIO.

LOOSE-LEAF BINDER.

Application filed October 20, 1923. Serial No. 671,653.

Our invention relates to book binding, and more particularly to a loose leaf binder and especially to the locking means by which the book covers or backs are detachably engaged with the leaf retaining posts.

The present invention relates more particularly to that type of loose leaf binder wherein the sheets or leaves are perforated and are assembled over the ends of posts or 10 retaining studs, which are detachably engaged with the book backs or covers as distinguished from those loose leaf books of the ledger type, wherein the sheets or leaves are slotted for engagement with posts or 15 pins, without passing them over the ends of the retaining members.

In the present invention there is contemplated a metal leaf or hinge, which is incorporated in the back or cover of the book, and 20 is provided with a hinge rod or trunnion pin laterally engageable in alined notches in a series of studs or posts extending perpendicularly through the leaves or sheets, such hinge rod or trunnion pin being held in operative engagement with the posts or studs 25 by a series of yokes pivoted upon the rod or pin, and normally embracing the protruding ends of the posts or studs to retain the rod or pin in the notches thereof, while the hinge 30 plate and cover swing to and fro. Normally the hinge plate or leaf swings independent of the retaining yoke. These yokes are interconnected into a series herein referred to as the yoke bar, and means is provided for interlocking the yoke bar with the hinge plate or leaf when the cover is in open position, so 35 that upon the closing movement of the cover or book back, the series of retaining yokes is simultaneously carried over the end of the 40 retaining posts or studs, in unison with the movement of the book cover and hinge plate, thereby releasing the hinge rod or trunnion pin from its engagement in the notches in the posts and permitting the removal or addition 45 of leaves to the posts or studs.

The object of the invention is to improve the structure, as well as the means and mode of operation of loose leaf binders whereby they will not only be simplified in construction and cheapened in production, but will be more efficient in use, capable of being easily and quickly operated, secure and durable, and unlikely to get out of repair.

A further object of the invention is to 55 provide a loose leaf binder construction, wherein the back or cover may be discon-

nected to enable the removal or addition of sheets or leaves in minimum space and without the necessity of withdrawing the hinge rod or trunnion pin, which under ordinary 60 circumstances is a rather inconvenient and awkward operation to perform.

A further object of the invention is to provide an interlocking means which will be 65 secure, yet simple and easily operable by means embodied in the structure, without the necessity of employing separable implements or tools.

With the above primary and other incidental objects in view as will more fully 70 appear in the specification, the invention consists in the features of construction, the parts and combinations thereof, and the mode of operation or their equivalents as 75 hereinafter described and set forth in the claims.

Referring to the accompanying drawings, wherein is shown the preferred, but obviously, not necessarily the only form of embodiment of the invention, Fig. 1 is a perspective view of an assembled record book, embodying the present invention, from which a portion of one back or cover and a portion of the leaves have been torn away to expose to view the operative parts of the binder. 80 Fig. 2 is a perspective view of the several parts of one of the hinge sections, detached from the book structure and disassembled into its component parts. Fig. 3 is a perspective view of one of the posts or studs, upon 85 which the perforated sheets or leaves are assembled. Fig. 4 is a detail perspective view of the locking means for the yoke bar. Figs. 5, 6 and 7 are plan views of the hinge sections including the retaining yoke bar and 90 trunnion pin in several positions of adjustment. In Fig. 5 the parts are shown in their normal relation, when the book is closed. Fig. 6 is an interior plan view, that is, with the book cover open. Fig. 7 is a top plan 100 view showing the hinge plate disconnected from the post or stud.

Like parts are indicated by similar characters of reference throughout the several views.

In the accompanying drawings, 1—1 indicates the book covers and 2 is the back to which the covers are hinged. The leaves or sheets 3 are removably secured between the covers 1—1 by being strung upon a series 110 of posts 4, which are of somewhat arcuate form, and are interconnected with the front

and rear covers 1—1 on their hinge lines. The sheets 3 are provided with perforations adjacent to their rear edges, which register with the posts 4, and through which the 5 posts 4 extend. To remove or add sheets or leaves 3, it is necessary to disconnect the 10 posts 4 at one end from the connecting cover 1, which permits the perforated sheets or leaves 3 to be passed over the ends of the 15 posts. The posts are positioned with their convex sides directed forwardly or toward the open side of the book, and are provided with notches 5 in the convex face and adjacent to the ends of the post to receive the hinge rod, or trunnion pin, which is held therein by a yoke extending about the opposite side of the post.

Secured to the inner faces of the book covers 1—1 by riveting or otherwise, so 20 that it becomes an integral part of the cover is a metallic hinge plate 6. The rearward edge of the hinge plate 6 is formed with a series of notches or recesses 7, registering with the posts 4 and within which the posts 25 extend when the structure is assembled. The rear margins of the plate 6 is turned upon itself intermediate the notches or recesses 7 to form hinge sleeves 8 to receive an elongated hinge rod or trunnion pin 9. The 30 trunnion pin 9, extending through hinge sleeve 8 from one end of the plate 6 to the other, traverses the notches or recesses 7, within which the pin is exposed. When 35 assembled such exposed portion of the hinge rod or trunnion pin 9 engages in the open side notches 5 of the posts 4. These notches 5 being alined with each other, the hinge rod or trunnion pin 9 is movable to and out of the notches by a to and fro shifting movement of the cover 1.

To limit the relative movement of the cover sections 1—1, and prevent disengagement of the trunnion pin 9 from the notches 5, a series of yokes 10 are provided which 45 are pivoted upon the trunnion pin 9 within the recesses 7, engaging the trunnion pin on opposite sides of the posts 4. By extending around the post 4, these yokes 10 hold the trunnion pin within the notches 5 and 50 prevent its disengagement therefrom. In order that the posts 4 may be engaged and disengaged by a unison movement of the yokes 10, these yokes are interconnected by an intermediate integral tie portion 11, thus 55 forming a continuous integral structure hereinafter referred to as the yoke bar. The yoke bar is spring pressed into extended position, that is, with the yokes 10 extended outwardly and away from the plate 6 by 60 means of helical springs 12, surrounding the trunnion pin 9 and engaging at one end with the yoke bar and at the other with the hinge plate. These springs 12 tend to turn the yoke bar outwardly and downwardly over 65 the ends of the posts 4. The yokes 10 are

thus held in engaging position about the posts by the influence of the spring 12, while the hinge plate 6 attached to the cover 1 may oscillate to and fro about the trunnion pin 9, which maintains its engagement with- 70 in the grooves 5 of the posts.

When it is desired to disconnect the hinge plate 6 and cover, from the post 4, to permit the removal or addition of sheets 3, the cover is turned to the wide open position, 75 wherein the hinge plate 6 being passed over the top of the posts projects backward therefrom. This is the normal relation of the parts whenever the book is open to full extent. However, if the back is to be disengaged, the yoke bar is interengaged or locked in its relation with the hinge plate when the plate is in such open position as shown in Fig. 6, whereby upon the subsequent closing of the book, the yoke bar will 80 be oscillated in unison with the hinge plate 6 and the yokes will pass over the tops of the posts 4 thereby disengaging the posts and allowing the trunnion pin 9 to be drawn away from the notches 5. The cover is 85 thereby disengaged and when laid back exposes the end of the post for removal or replacement of sheets 3.

To interlock the hinge plate 6 and yoke bar for such disengaging return oscillation, 90 there is provided at a medial point upon the plate a detent member 13, which may be pivoted thereto or may be loosely mounted for sliding or oscillatory movement. In the present instance the detent 13 has been 95 shown provided with an extension or finger 25, loosely engaged within a keeper or loop 26, projecting from the inner face of the plate. The detent 13 is located coincident with an enlarged notch or recess 14, similar 100 to the notches or recesses 7, but of greater extent, and preferably located at the middle of the plate. The yoke bar is provided with a corresponding yoke 15, pivoted upon the trunnion pin 9, as are the yokes 10, and movable into and out of the enlarged notch or recess 14, as the parts are relatively turned about the trunnion pin. The detent member 13 is provided with a nose or overhanging beak portion 16, which is movable into and 105 out of engagement with a shoulder 17 upon the yoke 15, when the cover is in open position as shown in Fig. 6, with the several yokes 10 and 15, positioned within their respective notches or recesses. The detent is urged into locking engagement with such shoulder, by a compression spring 19, surrounding the pin 9 and bearing against an ear 20 upon the detent. To disengage the 110 detent from its locking engagement with the yoke bar and hold it in its normally retracted position, there is pivoted upon the trunnion pin 9 within the enlarged medial recess 14, an independent bail or yoke 21. The bail or yoke 21 and the yoke bar em- 115

bodying the yokes 10 and 15 are adapted to oscillate about their pivotal engagement upon the trunnion pin independently of each other. The bail or yoke 21 is provided with a shoulder or lip 22, engageable in a cam notch 23 in the detent member 13. Upon a partial rotation of the bail or yoke 21 by action of the spring 19 as hereinafter explained, the shoulder or lip 22, by its engagement in the cam notch 23 will retract the detent against the expansive force of the same spring 19, to withdraw the locking nose or beak 17 and hold the detent in its retracted position. The detent is thus held retracted during the normal use of the book. When so retracted the hinge plate 6 may be oscillated to and fro independently of the yoke bar. Upon reverse rotary movement of the bail or yoke 21, which is affected manually the lip or shoulder 22 is withdrawn from the cam notch 23 allowing the detent to interlock the yoke bar and hinge plate, so that upon the next closing movement of the book cover, the yokes 10 will swing over the ends of the posts against the force of spring 12 in unison with the movement of the cover and hinge plate.

The bail 21 is capable of a limited reciprocatory movement upon the trunnion rod 9 within the range prescribed by a limiting stop finger 24 bent laterally over the enclosing yoke 15. The spring 19 exerts its tension in opposite directions. It bears against the ear 20 at one end tending to shift the detent 13 into engagement with the shoulder 17 of the yoke 15, while at the opposite end it tends to shift the bail 21 in the opposite direction and move its shoulder or lip 22 out of registry with the cam notch 23. Furthermore the end of the spring 19 is caught around one arm of the bail 21 so that it exerts its torsional influence to oscillate the shoulder or lip 22 of the bail 21 into engagement with the detent. By a slight reciprocation of the bail 21 manually against the tension of the spring 19, the shoulder 22 is brought into alignment with the cam notch 23 into which it enters under the torsional influence of the spring 19, and by its camming action retracts the detent 13 to release the yoke bar. Upon turning the bail 21 against the torsional tension of the spring 19 to withdraw the lip 22 from the notch the detent is actuated into engaging position by the expansion of the spring 19.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described our invention, we claim:

1. In a loose leaf binder, a plurality of binding posts to receive the leaves to be bound, a hinge plate, a trunnion member carried by the hinge plate and having lateral engagement with the posts, a plurality of retaining yokes pivoted upon the trunnion member and normally enclosing the posts to retain the engagement of said parts, the yoke and hinge plate being independently movable in relation with each other, and means for interlocking the yokes and hinge plate for unison movement into disengaging position.

2. In a loose leaf binder, a plurality of binding posts to receive the leaves to be bound, a hinge plate, a trunnion member carried by the hinge plate and having lateral engagement with the posts, a plurality of retaining yokes pivoted upon the trunnion member and normally enclosing the posts to retain the engagement of said parts, the yoke and hinge plate being independently movable in relation with each other, a detent engageable with the yokes when the hinge plate is oscillated to open position and by which the yokes are carried over the ends of the posts upon return oscillation of the hinge plate to release the hinge plate from the posts.

3. In a loose leaf binder, a plurality of binding posts to receive the leaves to be bound, a hinge plate detachably engageable with the posts for oscillatory movement to and fro, means for interlocking the hinge plate with the posts independent of which the plate normally oscillates, and means for interlocking the retaining means and plate for unison movement by which the retaining means is disengaged from the posts by oscillatory movement of the hinge plate.

4. In a loose leaf binder, a plurality of binding posts, a hinge plate, a yoke bar detachably connecting the plate with the posts for oscillatory movement independent of the yoke bar, a detent for interlocking the hinge plate and yoke bar when the hinge plate is in one position of adjustment for unison movement by which the yoke bar is disengaged from the posts upon return oscillation of the hinge plate.

5. In a loose leaf binder, a plurality of

binding posts, a hinge plate, a yoke bar detachably connecting the plate with the posts for oscillatory movement independent of the yoke bar, a spring pressed detent for interlocking the yoke bar and hinge plate for unison movement to disengaged position.

6. In a loose leaf binder, a plurality of binding posts, a hinge plate, a yoke bar detachably connecting the plate with the posts for oscillatory movement independent of the yoke bar, a spring pressed detent for interlocking the yoke bar and plate, and manually operable means for normally holding the detent inoperative and for releasing the detent for effecting unison movement of the yoke and plate to disengaged position.

7. In a loose leaf binder, a plurality of binding posts, a hinge plate, a yoke bar detachably connecting the plate with the posts for oscillatory movement independent of the yoke bar, a stop shoulder upon the yoke bar, a detent movable into and out of engagement with the stop shoulder, and an independently manually operated control member having cam engagement with the detent, the yoke bar and plate being interengaged by the detent for unison movement to disengaged relation with the posts.

8. In a loose leaf binder, a plurality of posts upon which perforated leaves are strung, said posts being laterally notched, a hinge plate attached to a cover section, a trunnion rod carried by the hinge plate and engageable laterally in the notches of the posts, and yokes carried by the trunnion rod and surrounding the posts to hold the rod within the notches.

9. In a loose leaf binder, a series of binding posts to receive the leaves to be bound, a hinged cover section laterally engageable with the binding posts for to and fro oscillatory movement, and retaining members engageable over the ends of the posts for detachably securing the hinged cover section in lateral engagement with the posts.

10. In a loose leaf binder, a series of binding posts to receive the leaves to be bound, a hinged cover section a trunnion rod upon which the cover section is hinged, and laterally engageable with the binding posts to enable to and fro oscillatory movement of the latter, and an additional member for simultaneously engaging and disengaging the several posts to hold them in their relation with the trunnion rod.

11. In a loose leaf binder, a plurality of binding posts to receive the leaves to be bound, a hinged section laterally engageable with the posts, for to and fro movement, and a series of yokes, one for each post carried by the hinged section and detachably enclosing the posts to maintain operative engagement of the hinged section therewith.

12. In a loose leaf binder, a plurality of

binding posts to receive the leaves to be bound, a hinged section laterally engageable with the posts, for to and fro movement, and a series of interconnected yokes carried by the hinge and detachably engaging the posts to maintain the lateral engagement of the hinged section therewith, said interconnected yokes being operable in unison to connect and disconnect the posts and hinged section.

13. An arcuate binding post for a loose leaf binder, having inwardly convergent lateral notches adjacent to its opposite ends and upon the convex side of the arcuate post into and out of which a round trunnion may freely pass.

14. A binding post for a loose leaf binder having semi-circular lateral notches adjacent to its opposite ends for loose sealing engagement of a trunnion member upon a cover section.

15. In a loose leaf binder, a plurality of binding posts to receive the leaves to be bound, said posts having notches therein to receive a trunnion member of a hinged cover, a trunnion rod upon a cover section engageable laterally within the notches of the posts, and retaining yokes pivotally engaging the trunnion rod upon the opposite side of the respective posts and extending about the posts to detachably hold the rod within the notches.

16. In a loose leaf binder, a plurality of binding posts to receive the leaves to be bound, said posts having notches therein to receive a trunnion member, of a hinged cover, a trunnion rod upon a cover section engageable laterally within the notches of the posts, and retaining yokes pivotally engaging the trunnion rod upon the opposite side of the respective posts and extending about the posts to detachably hold the rod within the notches and means to effect the simultaneous oscillation of the yokes over the ends of the posts to release the posts from the rod.

17. A hinge leaf for a loose leaf binder comprising a swinging plate for attachment to the binder cover having in the marginal edge a series of notches adapted to register with a plurality of binding posts, over the edge of which the plate is adapted to be turned to and fro the margin of the plate intermediate the notches being turned upon itself to form a succession of hinge sleeves, a trunnion rod engaged therein traversing the notches and laterally engaged by the posts in an inwardly facing relation with the notches in one position of the swinging plate, and in outwardly facing relation with the notches in reverse position of the plate.

18. In a loose leaf binder, a plurality of binding posts to receive the leaves to be bound, and having lateral notches in their faces outwardly directed toward the open

side of the binder and adjacent to their ends, a hinge leaf comprising a swinging plate having marginal notches registering with the posts and within which the posts project 5 trunnion carried by the hinge leaf and traversing the notches thereof, said trunnion having lateral engagement in the outwardly directed notches of the posts, and means for detachably retaining said trunnion within 10 the post notches.

19. In a loose leaf binder, a plurality of binding posts to receive the leaves to be bound, and having lateral notches therein, a hinge plate having notches registering 15 with the posts, a trunnion rod carried by the plate and traversing the notches thereof, said rod being laterally engageable in the notches of the posts, a yoke bar comprising a series of yokes one for each post pivoted 20 upon the trunnion rod and enclosing the

posts to hold the rod within the notches in the posts, said yokes being spring-pressed into engagement with the posts.

20. In a loose leaf binder, a plurality of binding posts, a hinge plate detachably connected with the posts for oscillatory movement, a retaining member normally engaging the posts to hold the hinge plate in close relation therewith, said hinge plate being normally movable to and fro independent of the retaining member, and means for interlocking the retaining member with the hinge plate for unison oscillation to release the posts.

In testimony whereof, we have hereunto set our hands this 16th day of October A. D. 1923.

HENRY G. CLARK.
LOUIS S. CLARK.
